H. W. CLOTHIER ET AL

ELECTRIC WALL PLUG AND LIKE FITTING

Filed April 21, 1925

UNITED STATES PATENT OFFICE.

HENRY WILLIAM CLOTHIER, OF WALLSEND-ON-TYNE, AND HAROLD FREDERIC SECRETAN, OF PELAW-ON-TYNE, ENGLAND, ASSIGNEES TO A. REYROLLE & COMPANY LIMITED, OF HEBBURN-ON-TYNE, ENGLAND, A COMPANY OF GREAT BRITAIN.

ELECTRIC WALL PLUG AND LIKE FITTING.

Application filed April 21, 1925, Serial No. 24,855, and in Great Britain May 30, 1924.

This invention relates to electric wall plugs and like fittings.

Fittings of this type are now often used for supplying power for various household purposes as for instance portable lamps, electrically driven carpet sweepers, electric heaters, etc., and the primary object of this invention is to provide for the supply of power for two or more of such uses from one point

10 on the mains.

An electric wall plug or like fitting according to this invention is so constructed that two or more subsidiary circuits each protected by its own fuse may be connected to

15 the supply through one main fitting.

In the following description it is to be understood that the terms "plug" and "socket" are interchangeable, that is to say a fixed socket member referred to as cooperating with a movable pin or plug member is equivalent to a fixed plug member cooperating with a movable socket member.

In one construction of fitting according to this invention the fitting has at one end a pin or plug member adapted to cooperate in the usual way with a fixed socket member connected to the supply mains. From this one plug member there are three branches each terminating in three socket members, one central and one on each side of it. The body of the fitting is of moulded insulating material and the electrical connections from the main plug member to each of the three branches are conveniently embedded in this moulded material provision being made for a separate fuse for each of the branch circuits such fuse being inside the fitting and easily removable.

The intermediate part of the fitting i. e. 40 that between the main plug member and the branch socket members is preferably of triangular form in side elevation and is covered by a metal casing made in two parts secured in position by any convenient means.

45 A removable plug member is provided cooperating with each of the branch socket members and each of these plug members may be connected to any desired apparatus or subsidiary circuit.

50 If during use a fault occurs on any subsidiary circuit this will merely have the effect of blowing the fuse in the particular branch circuit without affecting the fuse of

larger size which protects the fitting as a whole.

55 The above description is given by way of example as that of a wall plug or like connection for three subsidiary circuits but obviously a somewhat similar construction may be used in a fitting for two or more than three of such circuits.

In the accompanying drawings,

Figure 1 is a side elevation partly in section of a three-way plug and socket fitting according to this invention,

60 Figure 2 is a perspective view of one of the fuses,

Figure 3 is a plan of the fitting with the top part of the cover removed, and

65 Figure 4 is a perspective view of a modified form of two-way fitting also according to this invention.

70 With reference first to Figures 1, 2 and 3, A is the fixed socket member of a wall plug shown in position on a wall B. The improved fitting comprises a main plug member C adapted to engage with the socket member A, a body D of insulating material and three branch socket members E, E', and E''. All the parts are enclosed in metal casings and the casing F of the body D has its upper portion made so that it can be readily removed to give access to the connections and fuses within it.

75 Each branch circuit to the socket members E, E', and E'' is provided with two fuses contained within the body D of insulating material, and the three branch circuits are connected in parallel to the pins of the main plug member C. Each fuse wire G is wound in grooves on a bobbin or block G' (Figure 2) which is contained in a recess in the body D. Conveniently the body is made in two parts so that the recesses form a series of

80 boxes or cavities closed by a lid-like portion D' of the block. Projections D'' on the inside of this portion D' press the ends of the fuse wires G into contact with small metal blocks H which are themselves in connection with the leads of the branch circuits.

85 As indicated in Figure 1, distance pieces D''' are formed on the body D and its cover D' so that when the removable portion of the casing F is placed in position and secured by the screws F' the two portions of the body D are clamped tightly together.

With the branch socket members E, E' and E² cooperate any convenient forms of plug members, one of which is shown at J.

Figure 4 is a perspective outside view of another fitting according to this invention. Its internal construction is similar to that described with reference to Figures 1, 2 and 3 except that provision is made for two instead of three branch circuits. As in the form previously described, the whole fitting is enclosed in metal and provision is made for ensuring that the casing is adequately earthed in accordance with good present day practice. Screws K for the earthing connections 15 are shown in both forms.

What we claim as our invention and desire to secure by Letters Patent:—

In an electric plug and socket fitting the combination of a main plug member adapted 20 to cooperate with a fixed socket member, a

plurality of branch socket members, a body of moulded insulating material in two parts, one of said parts having internal recesses said body being between the main plug member and the branch socket members, bobbins accommodated in said recesses, fuses carried on said bobbins and electrically connecting each branch socket member with the main plug member, a casing mechanically connecting the main plug member and the branch socket members and containing within it the two part body of moulded insulating material, and a removable cover for said casing serving when in position to hold the two parts of the body together. 30 35

In testimony whereof we have signed our names to this specification.

HENRY WILLIAM CLOTHIER.
HAROLD FREDERIC SECRETAN.
